GOLF CLUB CASE

Chester H. Johnson, Minneapolis, Minn.

Application July 9, 1946, Serial No. 682,371

3 Claims. (Cl. 150—1.5)

1

The object of the invention is to provide a golf club case embodying a rigid but comparatively light frame in which golf clubs may be held in an orderly manner, so that they will be prevented from impact with one another when being transported and will also be readily observable individually for selection in playing the game of golf; to provide a case of the kind indicated which includes a storage compartment for tees and golf balls and which supports in accessible position a limited number of tees and balls for immediate use; to provide a case of the kind specified in which the frame is enclosed with a removable cover and equipped with carrying means that make it susceptible of transporting by hand or support from the shoulder; and generally to provide a golf club case comprising the features mentioned but which may be cheaply manufactured and marketed.

With this object in view the invention consists of a construction and combination of parts of which a preferred embodiment is illustrated in the accompanying drawings in which:

Figure 1 is a central vertical sectional view of the invention;

Figure 2 is a top plan view of the frame, the standards being shown in section;

Figure 3 is a cross-sectional view of the frame just above the plane of the top of the storage compartment; and

Figure 4 is a cross-sectional view of the frame just above the plane of the base plate.

The frame which, when the case is not in use, is enclosed with a removable cover 10, is composed of the spaced plates 11, 12 and 13 and the standards 14 and 15, the former being of generally oval form with the standards passing through them and being fixedly secured thereto by means of pins driven in the edges of the plates and passing diametrically through the standards. By means of this arrangement the plates and standards are fabricated into a rigid frame of which the top and base plates 13 and 11 serve as the supporting means for golf clubs, such as indicated at 17 in Figure 1.

In order that the clubs so supported may be held in spaced relation and thus be susceptible of quick selection by a player, the top plate 13, throughout its perimeter, except the heel or that part between the two standards 15, is provided with clips 18 of generally rectangular form and clips 18a of generally triangular form. The facing sides of adjacent clips are inwardly curved so that the curved portion of the one is complementary to the curved portion of the other thus

forming a seat 19 for the shaft of the golf club just below the head thereof. Being made of spring metal, the clips yield in withdrawing or inserting a golf club shaft.

5 The lower ends of the golf club shafts, when a full complement are mounted in the several seats, rest on the base plate 11 just within the metal band 20 peripherally attached to the base plate with its lower edge flush with the bottom face of the base plate and its upper edge well above the top face of the latter. The band thus acts as a guard to keep the lower ends of the shafts within the area of the base plate.

10 Mounted centrally on the base plate 11 is a storage case for tees, balls et cetera, this case having the same contour cross-sectionally as the base plate but being of less perimeter than the latter, so that adequate rest space for the golf club shafts may obtain between the band 20 and the storage case. This storage case is composed of a base 21 secured to the base plate 11, a shell 22, preferably of metal, rising from the base 21, extending through the plate 12 and opening on the top face of the latter, being closed at this upper end with a cover 23 hinged, as at 24, to the plate 12 and equipped with a hand knob 25.

15 On the top plate 13 balls and tees for immediate use are conveniently supported and to that end the top plate is formed with openings 26 of the contour of zones of spheres of the same diameter as that of golf balls, these openings constituting ball seats. These openings are covered with a removable guard 27 of cylindrical form and open on the under side and closed on top. On 20 the under side of the top, at the center, is an internally threaded socket 28 which is engaged with or disengaged from the threaded post 29 positioned symmetrically with respect to the ball seats 26 and secured to the plate 13 through the 25 instrumentality of its head 30 and lock-nut 31 which abut respectively the bottom and top faces of the plate 13. Removal or replacement of the guard is accomplished by rotating it bodily in the proper direction to disengage it from or engage it with the post 29, the lower edge of the guard frictionally engaging the top face of the plate 13 in the attached position when it covers the balls and retains them in their seats.

20 To provide for keeping tees available for immediate use, the guard 27 (as illustrated) or the plate 13 is formed with uniformly spaced holes which serve as seats for tees 32 which will readily keep their places therein whether the guard be in its closure position or not.

25 In order that the contents of the frame may be

shielded and rendered inaccessible to unauthorized persons, the cover 10 is provided. This cover is removable in its entirety. When attached to the frame, however, it entirely encloses the latter. Of generally tubular form, the cover is closed at the upper end just below which it is provided, on the side wall, with a fabric strip sewed thereto to form a downwardly opening pocket in which is received the upper ends of the standards 15 which are joined by a bowed section 34, the two standards being integral parts of the same rod bent to bring the two sections constituting the standards into parallelism.

The cover 10 is formed with a clearance opening 35 just below the plane of the plate 13 for the handle 36 and shoulder strap 37, the two being secured to the standards 15. Below the opening 35 and extending therefrom to the lower open end, the cover is split and the edges of the same are equipped with rows of teeth constituting the intercurrent teeth 38 of a slide fastener of which the slide 39 carries a swinging combination finger piece and hasp 40 engageable with a post 41 on the perimeter of the base plate 11, the post having an opening in which is received the shackle of a lock 42.

On the band 20 diametrically opposite the post 41 is the male member of a snap fastener 43 of which the female member is attached to the cover 10. By this means the cover is detachably secured to the frame at a point remote from the post 41 as well as at the post.

It is obvious that the case may be carried by hand through the medium of the handle 36 or supported from the shoulder by looping the strap 37 over the latter; that the case will stand upright on its base plate 11; that the frame and its contents are completely enclosed and the contents protected from surreptitious removal when the cover is attached; that the cover may be removed in its entirety to make all of the various contained clubs readily accessible; and that the clips 48 form positive means for retaining the clubs in separated positions from which any selected club may be readily withdrawn.

The invention having been described, what is claimed as new and useful is:

1. A golf club case comprising a frame, means

carried by the frame for racking golf clubs in separated positions, and a removable cover enclosing the frame, the latter embodying spaced parallel plates and standards spanning the plates, at least two of the standards being joined at their upper ends with a bowed element and the cover having an interiorly positioned inverted pocket in which said upper ends and bowed element are received.

- 10 2. A golf club case comprising a frame, means carried by the frame for racking golf clubs in separated positions, and a removable cover enclosing the frame, the latter embodying spaced parallel plates and standards spanning the plates, at least two of the standards being joined at their upper ends with a bowed element and the cover having an interiorly positioned inverted pocket in which said upper ends and bowed element are received, the cover also having a side split extending from its bottom edge to a point just below the uppermost of said plates, and a slide fastener releasably closing said slit and having its slide provided with an element engaging a complementary element on the lowermost of said plates.
- 20 3. In a golf club case, a frame member having symmetrically arranged golf ball seats formed in the top thereof, and a removable guard covering said seats, the frame member having a threaded post centrally and symmetrically positioned with respect to said seats and the guard having an interiorly positioned internally threaded socket engageable with said post.
- 25 30
